UNITED STATES PATENT OFFICE

ARTHUR J. SLAGTER, OF MUSKOGEE, OKLAHOMA, ASSIGNOR TO TRANSCONTINENTAL OIL COMPANY, OF PITTSBURGH, PENNSYLVANIA, A CORPORATION OF DELAWARE

METHOD AND APPARATUS FOR PROCESSING HEAVY OILS

Application filed March 28, 1924. Serial No. 702,565.

This invention relates to a method of processing heavy oils, such as gas oil and to new and improved apparatus for carrying forward the method.

5 An object of the invention is to produce a method of processing such heavy oils whereby a greater yield of high volatile fractions is obtained and in which the quality of such fractions is better than has heretofore been 10 obtained by methods now in use and known to me.

A further object is to produce an improved method such that a greater volume of distillate may be effectively processed in a unit of 15 time without materially increasing the expense of the apparatus employed or without increasing the size of such apparatus.

20 A further object is to produce a method of processing heavy oil distillates, and apparatus for accomplishing the method, in which a more uniform and greater heat transfer from the source of heat to the distillate is accomplished and in which the production of the 25 high volatile fractions is improved both from the standpoint of quantity and quality and the deposition of carbon within the still is reduced to a minimum.

25 A further and more specific object of the invention is to produce a method of processing heavy hydro-carbons, such as fuel oils and heavy natural crudes, in which an improved quality and increased quantity of the volatile fractions is obtained and in which the process may be continuously carried forward for relatively long periods as compared to present methods employed in oil cracking or distillation processes.

30 These and other objects which will be made more apparent throughout the further description of the invention are attained by means of the methods herein set forth and the apparatus herein illustrated and described.

35 In the drawings accompanying and forming a part hereof, Figure 1 is a more or less diagrammatic view of apparatus embodying my invention. Fig. 2 is a front elevation of a portion of the apparatus shown in Fig. 1. Fig. 3 is a front elevation of a portion of the apparatus shown in Fig. 1, which may be em-

ployed as an auxiliary to the apparatus disclosed in Fig. 2. Fig. 4 is a detail of a portion of the apparatus disclosed in Figs. 2 and 3. Fig. 5 is a modified form of apparatus for carrying forward a modification of the 55 method of processing employed in connection with the apparatus illustrated in Figs. 1 and 3. Fig. 6 is a diagrammatic detail of view of a portion of the apparatus shown in Fig. 5; and Fig. 7 is a further modified form of 60 apparatus which may be employed in carrying forward a substantially continuous method of processing heavy hydro-carbons or distillates.

The inventions herein set forth are particularly applicable to oil-cracking operations, which distinguished from the usual and well-known distillation processes in that the molecular character of the high volatile fractions resulting from the method of processing 70 is modified by the application of heat under the conditions encountered.

75 In the present invention, I employ a still, similar in general characteristics to the stills employed in ordinary distillation and oil-cracking processes. For example, the still 8 disclosed in Fig. 1 may be of the ordinary type which is heated by a furnace 8^a located below it. The method of processing employed by me, however, distinguishes from the ordinary distillation process in that the distillate is maintained under a pressure approximately eighty pounds above atmosphere, and the products given off by the still are maintained under this pressure while being sprayed with 80 raw distillate, which is subsequently delivered to the still, and while being further cooled to a predetermined temperature by a gradual reduction of the heat carried by them.

85 As illustrated, in Fig. 1, the high volatile fractions, or the gaseous products resulting from the method of processing, are withdrawn from the still through a pipe or passage 9 which communicates with a header 10 forming a part of apparatus which may be termed a "dephlegmator". At least two risers or pipes communicate with the header 10 and extend vertically to a second header 12. These pipes are preferably exposed to atmospheric temperatures and are of such di-

5 ameter as to provide a large cooling surface per unit of volume of the gaseous product passing through them. For example, in apparatus employed by me, the pipes 11 are of 10-inch diameter throughout the major portion of their length but are reduced to approximately 6 inches in diameter at the junction with the header 12 for the purpose of 10 directing the flow of gaseous products issuing from them and insuring an intimate mixture 15 of these products with raw distillate delivered to the header 12 in the form of spray.

15 As shown in Fig. 4, a spray pipe 13 extends longitudinally throughout the length of the header 12 and is provided with spray nozzles or orifices 14 which are spaced along the spray pipe to correspond with the spacing of the pipes 11. In order to provide a uniform 20 delivery of raw distillate spray to each of the risers 11, the orifices 14 are reduced in diameter from the inlet end of the spray pipe so that the orifice of largest diameter is most remote 25 from the inlet end of the spray pipe. In practice, I have found that satisfactory results are obtained with the spray-delivery orifice immediately adjacent to the inlet end of the spray pipe $\frac{3}{2}$ " in diameter and with each successive orifice increased by $\frac{1}{2}$ " in diameter. Each orifice is located immediately 30 above the delivery end of a riser 11, and the orifices are directed downwardly, and are of such size, relatively to the outlets of the risers 11, that the entire cross sectional area of the outlet of each riser is completely filled with 35 spray. I have also obtained satisfactory results by delivering the raw distillate to the supply pipe under a pressure varying from 125 to 150 pounds above atmosphere where the pressure within the header 12, and communicating passages, is maintained at eighty 40 pounds above atmosphere.

45 With the arrangement of apparatus employed, the gaseous products delivered from the still are intimately mixed with the spray issuing from the spray pipe 13 and are further subjected to the expansion of the raw fractions occasioned by the reduction in pressure and the increase in temperature to which they are subjected on being sprayed within 50 the header 12. This intimate mixture of the hot gaseous products with the raw fractions occasions a reaction within the header 10, pipes 11 and header 12, which improves both the processing operation and the quality of 55 the material resulting from this operation.

60 It appears that the intimate mixture of these products and the raw fractions, occasions a chemical reaction between the high volatile fractions of the raw distillate, which are liberated by the expansion and the heat to which they are subjected in the header 12, and pipe 11, and that these high volatile fractions combine or unite with the high volatile fractions resulting both from the distillation and cracking process. In addition to

70 this, the counter-current flow of the raw fractions, with relation to the flow of hot gaseous products up through the risers 11, occasions a carrying back of the lower volatile fractions, which may be liberated from the distillate in the still, and consequently these fractions are at least partially condensed and entrained by the raw distillate and returned to the still.

75 This operation also appears to improve the quality of the products of the processing operation over that which would be obtained if this condensate or low volatile material were returned to the still independently of the raw distillate. In addition to this, the 80 continuous delivery of the raw distillate to the still during the method of processing, improves the operation of the method, since it tends to reduce the deposition of carbon within the still and, of course, continues the 85 operation for a longer period and increases the amount of distillate which is acted upon during a single run. In practice, I preferably deliver raw distillate during the 90 processing operation in amounts equal to about one-third of the products given-off. This proportion may, however, be varied by varying the temperature conditions and it also may be varied for different qualities of 95 the raw distillate employed.

95 A second series of vertical pipes or passages communicates with and extends above the header 12. In Fig. 1, these pipes are indicated by the reference numeral 15 and they communicate at their upper ends with a 100 header 16. The header 16 is provided with an outlet pipe or passage 17 which may communicate directly with a water-cooled condenser 18, but which is provided with a relief valve 19 for controlling the delivery to 105 the condenser and incidentally for controlling the pressures maintained within the still 110 8, the headers 10, 12 and 16 and the communicating passages. It will, of course, be apparent that this valve, when opened more or less, will maintain the pressure within 115 the communicating passages only by reason of the application of heat to the still 8 and the resultant flow of gaseous products from the still. Under operating conditions, the 120 gaseous products traversing the passage 17 will be delivered directly to the condenser 18 if their temperature is approximately 400 degrees F. If this temperature is exceeded an appreciable amount, I employ a secondary 125 reaction chamber similar to the apparatus described in connection with the headers 10, 12 and 16 and illustrated in Fig. 3 of the drawings.

130 As illustrated, this secondary apparatus consists of a header 20 which is provided with risers or pipes 21 corresponding in location and function to the risers 11. These risers are reduced in diameter at their upper ends and communicate with a header 22

which is equipped with an oil spray pipe 23 corresponding to the oil spray pipe 13. The header 22 is also provided with vertically extending communicating risers 25 which correspond to the risers 15 and which terminate in a header 26. As shown, the header 26 is provided with a delivery pipe 27 which is provided with a relief valve 29 and which communicates with the inlet end of the condenser 18.

As illustrated, the spray pipes 13 and 23 receive raw distillate through a pipe 30 and the delivery of this distillate to the spray pipes 13 and 23 is controlled by the valves 31 and 32, respectively. The delivery pipe 17 is also in communication with the header 20 through one or more pipes 33 which are provided with a valve 34. As shown, the pipes 33 communicate with each of the risers 21, but a single connection may be made between the pipe 17 and the header 20 if desired.

Under conditions such as above outlined, i. e., where the temperature of the gaseous products in the pipes 17 are materially in excess of 400 degrees F., the valve 29 is partially opened and the valve 19 is fully closed after the valve 34 has been fully opened. The valve 32 is also opened, it being understood that the valve 31 is open, and a valve 35, in a return 36 from the header 20 to the outlet pipe 9, is open. This return is also provided with a check valve 37 which is adapted to permit a free flow of liquid from the header 20 to the pipe 9 but to prevent a flow in the opposite direction.

Under conditions above set forth, the gaseous products issuing from the header 16 will pass through the piping 17 and 33 to the secondary apparatus where it is delivered to the risers or pipes 21 and is therefore subjected to a continuation of the slow cooling process to which it was subjected in traversing the risers 15 and the pipe 17. In addition, these gases delivered to the risers 21 are also subjected to a spray of raw distillate delivered into the outlet of each of the risers 21. As has been said these risers 21 are reduced in diameter at their upper ends for the purpose of directing the flow of gaseous products issuing from them and for insuring an intimate mixture of these products with the spray issuing from the spray pipe 23.

It will be apparent that the same reaction takes place in the risers 21 and the header 20 as took place in the headers 10 and risers 11, although the activity of this reaction may differ in degree from that of the former action, due to the fact that the temperatures are somewhat reduced. If, however, the temperatures encountered in the secondary apparatus are substantially the same as those encountered in the primary apparatus, viz: headers 10, 12 and 16 and communicating

passages, then the reaction occurring in the secondary apparatus will be substantially the same as that in the primary apparatus and the gaseous products will be cooled by their contact with the raw distillate, their chemical or atomic characteristic will also be modified by the chemical reaction between them and the high volatile fractions liberated by the instantaneous reduction in pressure and the high temperature to which the raw distillate is subjected, and also by the "carrying-back" operation occasioned by the counter-current flow of this distillate spray in moving downwardly through the risers 21 and the header 20.

If the rate of the operation of the still, and other conditions are such that the temperature of the gaseous products issuing from the header 26 is still materially above the desired temperature of 400 degrees F., I may employ additional apparatus corresponding to that illustrated in Fig. 3, since the most satisfactory results are obtained where the process is operated under such conditions that the gaseous products are delivered to the water-cooled condenser 18 at about 400 degrees F.

The primary and secondary dephlegmators and any additional dephlegmators which may be employed are all exposed to atmospheric temperatures and consequently the operation of the process may have to be slightly varied to compensate for varying atmospheric conditions. In other words, in extremely cold weather, I have found that it is desirable to heat the raw distillate introduced in the form of spray to a temperature not to exceed 100 degrees. Other conditions may be maintained substantially normal even under wide variations in temperature conditions by varying the heat applied to the still and by manipulation of the amount of spray delivered.

In Fig. 1, I have illustrated an emergency relief valve 38 in a passage between the outlet pipe 9 and the intake to the condenser 18. The valve is only opened under emergency conditions and for the purpose of preventing waste of products through a safety valve 39 with which the header 10 is equipped.

In Fig. 2, I have shown the outlet pipe 9 as having two branches. This corresponds to a well known practice in connection with stills and is accomplished by providing a T-connection in the outlet passages immediately adjacent to the outlet port of the still and then employing two sets of similar piping between this connection and the header 10. A similar arrangement of the pipe 36 is also illustrated in connection with Fig. 3. Where two pipes 36 are employed in connection with the header 20 each pipe will preferably communicate with one branch pipe 9.

In Figures 5 and 6 I have illustrated a modified form of the still employed in connection with the apparatus heretofore de-

scribed. This modification of the apparatus to some extent modifies the method of processing described and materially improves the quality of the product. As illustrated the 5 still is provided with means for maintaining a rapid and forced circulation of the distillate within the still and in addition means are employed for so circulating the raw fractions introduced during the operation of 10 processing that they are mixed with the oil in the still in approximately definite proportions and are delivered at a relatively high velocity to the hottest portion of the still.

As illustrated I employ a pump, shown 15 as a centrifugal pump 40, within the still. The intake or suction of this pump communicates with a trap 41 located in the top of the still and surrounding the outlet port 9^a through which the gaseous products are delivered to the outlet pipe 9. This trap receives the raw distillate as it flows in through the inlet port from the header 10 or the secondary header 20 of Fig. 1. As shown a pipe 42 connects the bottom of the trap with 20 the suction of the pump and this pipe is provided with an additional inlet opening which communicates with the interior of the still and receives oil from a predetermined level within the still. As shown this additional 25 opening consists of a short section of pipe 43 which extends upwardly well above the bottom of the still to the desired level within the well. The function of this pipe is to supply sufficient liquid to the intake of the pump to 30 satisfy the demand of the pump. Its further, and most important function is to insure a thorough mixing of the incoming raw fractions with the oil contained in the still and to maintain a uniform mixture throughout 35 all portions of the still. This uniformity of mixture within the still assures the maintenance of a uniform temperature throughout the mass of oil in the still. The outlet of the pump communicates with a distribution passage 44, which is preferably divided as shown 40 in Fig. 6 and which extends longitudinally of the still near its bottom. This passage is shown as formed of piping and is provided with delivery apertures which are equally 45 spaced along the passage and are so positioned with relation thereto that they deliver the liquid pumped through them downwardly and against the bottom of the still. In addition to this the aggregative area of 50 the apertures is approximately that of the outlet of the pump so as to insure uniform distribution of the pumped liquid throughout the entire length of the passage.

With this arrangement the heat transfer 55 from the furnace to the oil within the still is materially increased, since the connection currents set up within the still are greatly augmented by the forced circulation occasioned by the operation of the pump, and, in 60 addition, the flow from the pump occasions a

washing or scouring action over the hottest portions of the still and therefore effectively and efficiently carries away the heat occasioned by the furnace. This scouring action also minimizes the deposition of carbon within the still and in this respect maintains the heat transfer more or less uniform during the entire run. Another function of the pump and the distributing passage employed in connection with it, is that the high rate of discharge from this passage maintains a more or less turbulent circulation within the still and therefore prevents local excess heating. This prevents some portions of the still being more active in the evolution of the gaseous products than others and therefore insures uniformity of the gaseous products delivered from the still.

In Figure 7 I have illustrated a still further modification of the apparatus employed for carrying out my improved process and this modified form of apparatus also, to some extent varies the process. As there illustrated the apparatus consists of a heating chamber 45, which is equipped with coils 46 through which the oil is circulated during the processing operation. Any means may be employed for delivering heat to this chamber and I have diagrammatically shown an oil burner 47 for this purpose.

As illustrated both the inlet and the outlet of the coil 46 communicate with an expansion chamber 48 from which the lighter fractions are delivered and to which the raw distillate is also delivered.

Fundamentally this apparatus functions on the same principal as the apparatus illustrated in Figures 1 and 5 and is adapted to be employed in connection with a reaction chamber such as described in connection with the headers 10, 12 and 16 of Figure 1. For this reason I have illustrated the expansion chamber provided with an outlet port 9^b, which communicates with an outlet piping 9' having the same functions as the outlet piping 9 of Fig. 1, in that it delivers the hot gaseous products to a header chamber 10' which communicates with the risers 11' having the same functions as the risers 11 of Fig. 1. These risers also communicate with a header 12' equipped with a spray pipe as illustrated in Fig. 4 and also provided with risers 15' which correspond in function to the risers 15 of Fig. 1. The header 16' of this apparatus is shown directly connected to the intake of a water cooled condenser 18' by a relief pipe 17', having a relief valve 19'. It will also be apparent that the secondary apparatus disclosed in connection with Fig. 1 may be employed in connection with the apparatus just described.

The port 9^b is equipped with a trap 41' corresponding in function to the trap 41 of Figure 5 in that it provides an adequate outlet for the gaseous products and at the same time receives the raw fractions entering through

the piping 9'. As illustrated the expansion chamber is provided with a circulating pump 49, which is adapted to maintain a rapid and forced circulation through the coils 46. As shown the pump 49 is a centrifugal pump and its intake or suction communicates directly with the trap 41' through a pipe 50. An additional inlet for liquid from the expansion chamber is also provided in this pipe 50 and as shown consists of a short section of pipe 51 which extends upwardly to the desired level within the expansion chamber. With this arrangement the fractions entering the trap 41' are combined with oil contained in the upper part of the expansion chamber on being delivered to the pump and are not only thoroughly mixed with this oil but are delivered at a high velocity through the coils 46 and then to the upper portion of the expansion chamber.

This arrangement of apparatus while insuring an intimate mixture of the raw distillate with the oil in the expansion chamber, promotes temperature stratification within the expansion chamber, since the hot oil issuing from the heating coils 46 is not mixed with the incoming cold or cooler raw distillate. This is of material advantage, since the evolution of the lighter fractions and the cracking of these fractions is not impeded or affected in any way by a reduction in temperature occasioned by the incoming raw distillate. As a further result of this arrangement of apparatus the evolution of the lighter fractions takes place in the upper portion of the chamber 48 and the heavier residuum settles to the bottom of the chamber from which it may be withdrawn through either the branch pipe 52 or a branch pipe 53 which is located at a higher level in the chamber.

From the foregoing it will be apparent that raw fractions may be continually introduced into the expansion chamber and that the heavy residuum may also be continually withdrawn throughout the operation of the process. Where this is accomplished I deliver heat in such quantities to the coils 46 that the raw fractions of raw distillate may be introduced to the reaction chamber in such quantities as to replace the oil taken out as distillate or residuum.

It will also be apparent that the bottom portion of the expansion chamber is practically unaffected by the currents set up by the pump 49 and that therefore the settling operation is accomplished under ideal conditions. In addition to this the high velocity of travel of the oil passing through the coils 46, increases the heat transfer through these coils by the scouring action, and this in turn, prevents or at least minimizes the deposition of carbon within the coils, with the result that the process can be continued for indefinite periods without the necessity of shutting down for the purpose of cleaning the coils.

The forced and positive circulation through the coils 46 also make it possible to process heavier residuum or heavier natural crudes than could be processed successfully in apparatus such as illustrated in Figures 1 to 6.

It will, of course, be apparent that the driving shaft of the pump 40 of Fig. 5 and the driving shaft of the pump 49 of Figure 7 are to be provided with suitable stuffing boxes. I have found in practice that it is desirable to employ a relatively heavy and large stuffing box and to water cool the box for the purpose of protecting the packing against the heat of the still.

The apparatus illustrated in Fig. 7, while adapted for use in treating gas oils and similar distillates is particularly adapted for heavier oils, such as fuel oils and heavy natural crudes. As a matter of fact such elaborate apparatus is not necessary for the satisfactory treatment of any distillates except those heavy residuums to which I have referred. The apparatus of Fig. 7 is also particularly adapted for use where exceedingly high pressures are employed, such as pressures employed in the cracking of kerosene and like distillates. It is apparent that the various chambers may be reduced to a minimum size because of the continual withdrawal of the residuum and the continual delivery of the raw distillate. Then too, the portion of the apparatus subjected to the greatest temperature is formed of piped coils which are well adapted for high pressures and high temperatures.

What I claim is:

1. A method of treating petroleum oil which consists in heating a body of oil to a cracking temperature while subjecting it to pressure materially above atmospheric pressure, continuously withdrawing vaporous products resulting from said heating and slightly cooling the same while maintaining said pressure, continuously mixing said products with fresh oil and returning the liquid products of said mixing back to the body of oil forcing said liquid products to the hottest part of the body, and subjecting the vaporous products to gradual cooling while maintaining said pressure and further cooling said vaporous products after a reduction in pressure.

2. A process of treating oils having a high boiling point to produce therefrom lighter fractions having a low boiling point, which consists in heating a batch of oil to a cracking temperature while maintaining it under pressure substantially above atmospheric pressure, continuously withdrawing vaporous products of said heating while maintaining the pressure, and while slightly cooling said products, expanding fresh oil while delivering it in the form of spray into separately directed streams of said slightly cooled vaporous products, delivering the residue oil from

said spray to said batch in a continuous and unobstructed flow in intimate contact with the hot vaporous products withdrawn therefrom, and delivering such liquid products to a hotter portion of the batch, and then condensing the vaporous products after said treatment with fresh oil.

3. A process of treating heavy oil to produce oils having a lower boiling point, which consists in heating a batch of heavy oil to a cracking temperature in a still while maintaining it under pressure, continuously withdrawing lighter fractions from the still while maintaining the pressure, mixing the lighter fractions while hot and while under pressure with a finely divided spray of fresh oil, continuously delivering the liquid products of the mixture to the still in contact with the lighter fractions being withdrawn therefrom and positively forcing said liquid products to the hottest part of the still by a positive circulating means, gradually cooling the vaporous products of the mixing while maintaining said pressure and then condensing said vaporous products after expanding them to a lower pressure.

4. The process for treating heavy oil to produce fractions of lower boiling point, which consists in maintaining a body of heavy oil under pressure while circulating it at a high velocity and subjecting it to a cracking temperature, withdrawing vaporous products resulting from said heating, directing said vaporous products in well defined streams, subjecting all portions of each stream to a finely divided spray of fresh oil, delivering the residue of the oil from the spray to said body below the surface thereof and positively forcing it to the hottest portion of the body, gradually cooling said vaporous products after subjecting them to said spray and then expanding said products to atmospheric pressure and subjecting them to a condensing temperature.

5. The process of treating oils of high boiling point to produce lighter fractions having low boiling point, which consists in heating a body of oil in a still to a cracking temperature while maintaining it under pressure substantially above atmospheric pressure, maintaining a forced circulation of the oil within the still to produce a scouring action on the heated portion of the still, and withdrawing vaporous products resulting from said heating, subjecting said products to a finely divided spray of fresh oil and delivering residue of the oil from said spray to said body below the surface thereof and positively directing such fresh oil so delivered to the hottest portion of the still.

6. In an apparatus for processing oil, a receptacle for oil having a vapor delivery port formed in the top thereof, and a residuum delivery port formed in the bottom thereof, a pump located within said receptacle and

having its inlet submerged below the surface of the oil contained therein, a heating coil communicating with the outlet of said pump and with the top of said receptacle, and means for delivering fresh oil to said receptacle through said vapor delivery port and to the inlet of said pump.

7. An apparatus for processing oil comprising a still, a dephlegmator consisting of headers and risers for directing vaporous products passing therethrough into well defined streams, an unobstructed liquid and fluid passage from said still to said dephlegmator, and means for introducing a finely divided spray of fresh oil to each well defined stream of vaporous products traversing said dephlegmator and in counter current flow relation to said stream, and means for delivering the liquid products of said spray traversing said unobstructed passage to the hottest portion of said still and for maintaining a forced circulation of the liquid within the still.

8. An apparatus for processing oil comprising a container for oil having a vapor delivery port formed in the top thereof, a dephlegmator communicating with said port, means for delivering oil sprays to the vapor passages of said dephlegmator, a trap for receiving liquid delivered from said dephlegmator located within said container below said port, a circulating coil and a pump located within said container having its inlet communicating with the said trap and its outlet communicating with a circulating coil.

9. A method of treating petroleum oils, which consists in heating a quantity of oil in a still to a cracking temperature while maintaining it under pressure materially above atmospheric pressure, withdrawing vaporous products resulting from such heating from the upper part of said still, while maintaining said products under pressure, dividing the flow of said products into separate streams in which they are gradually cooled while under pressure, delivering fresh oil in the form of spray to each of such streams and passing the liquid product of such mixture of oil and hot vapors to said still in contact with vaporous products leaving said still.

In testimony whereof, I have hereunto subscribed my name this 25th day of February, 1924.

ARTHUR J. SLAGTER.
